QUICK ACTION VISE

William W. Swain, Oakland, Calif.

Application June 26, 1952, Serial No. 295,647

9 Claims. (Cl. 81—17)

1

This invention relates to improvements in work holding means and particularly to a vise which is manually instantly adjustable to the work by mere sliding of the movable jaw and which locks in position and grips the work through a relatively small angular movement of a hand lever, and which is instantly releasable through an opposite movement of the lever.

This invention concerns a vise which is free of threaded or rack type adjusting mechanism with the movable jaw freely slidable to the work with sequential locking of the movable jaw in adjusted position and gripping of the work through a single movement of a hand lever, thus providing a vise which is operable for gripping or release in an absolute minimum of time.

The objects and advantages of the invention are as follows:

First, to provide a vise with a movable jaw which is freely slidable to the work, and which through a relatively small angular movement of a hand lever sequentially locks the movable jaw in adjusted position and efficiently grips the work.

Second, to provide a vise as outlined which sequentially releases the jaw and frees the jaw on its support through an opposite slight angular movement of the lever for adjustment of the movable jaw to a different position.

Third, to provide a vise as outlined in which the means for locking the movable jaw in adjusted position consists of spaced tie rods which form the supports for the movable jaw, and lateral plungers with intervening cam member for forcing the plungers against the adjacent sides of the tie rods with the tie rods thus locked in their bearings, and a lever for operating said cam.

Fourth, to provide a vise as outlined in which said cam is mounted in a housing and with the cam having cam surfaces formed in its side faces for operating said plungers and having a cam peripherally formed to cooperate with the movable jaw for intense gripping and release of the movable jaw to and from the work.

Fifth, to provide a vise as outlined which is simple in construction, economical to manufacture, and which is relatively light to handle.

Sixth, to provide a vise as outlined which has four sides for parallel support on a surface with the work exposed for operation from either of the sides.

In describing the invention reference will be had to the accompanying drawings, in which:

Fig. 1 is a side elevation of the invention.

Fig. 2 is a top plan view of Fig. 1.

2

Fig. 3 is a section taken on line 3—3 of Fig. 2.

Fig. 4 is a section taken on line 4—4 of Fig. 2.

Fig. 5 is a section taken on line 5—5 of Fig. 2.

Fig. 6 is a view taken in the direction 6—6 on

5 Fig. 2.

Fig. 7 represents an enlarged fragmentary sectional view, and shows plunger-engaging cam portions formed in opposite side surfaces of a jaw-advancing circular cam.

10 The invention consists of a combined head plate and fixed jaw 10, a foot plate 11, tie rods 12 and 13 connecting the head plate and foot plate, a movable jaw 14 slidably supported on the tie rods, a combined locking and thrust member 15 which is coupled to the movable jaw for slight relative movement and also slidably supported on the tie rods.

The combined head plate and fixed jaw is angle shaped having the upstanding jaw portion 16 and base portion 17 provided with a slot 18 for bolting to a support. The tie rods have both ends turned to a reduced diameter as indicated at 19 to provide shoulders 20 with the reduced portions passing through passages provided in the head plate and foot plate, the ends of these reduced portions being threaded for the nuts 21, these head and foot plates being drawn tight against the shoulders to provide a rigid structure.

The fixed jaw is provided with tapped holes 22 and 23 for attachment of jigs or fixtures, and the inner face is recessed as indicated at 24 for jaw facing 25.

The movable jaw 14 is a relatively plain portion of steel provided in its inner face with a recess 26 for jaw facing 27, and has passages 28 for the tie rods 12 and 13, on which the jaw is slid able. The back of this jaw has spaced tapped holes 29 and 30 for motion-limiting screws 31 and 32.

The combined locking and thrust member 15 consists of a block of metal having passages 33 for the tie rods 12 and 13 on which the block is slid able, and is provided with a substantially rectangular passage 34 centrally in which a multiple cam 35 is pivoted as indicated at 36. This cam has cam surfaces 37 and 38 formed in its opposite faces, these cams having a rise of only about 0.010 inch, and cooperate with the locking plungers 39 and 40 which in turn are cooperative with the tie rods which are preferably flattened on their inner surfaces as indicated at 41 and 42. This cam also has a peripheral cam surface 43, the rise of the cam in the direction of the side cams being only about 0.010 inch also, since only sufficient cam action is required to 50 provide the final clamping action on the movable

jaw. The ends of the plunger holes are plugged as indicated at 44 to prevent entry of dirt or dust to the bearing for the tie rods.

The screws 31 and 32 limit the relative movements between the movable jaw and the combined locking and thrust member, the holes 45 therefore in the combined locking and thrust member being counterbored for the heads of the screws as indicated as 46 with the counterbore of sufficient depth to conceal the head with the underside of the head functioning as a stop in cooperation with the bottom of the counterbore. A ball-end handle 47 is releasably fixed in the back of the cam, for manual operation.

The foot plate 11 is recessed as indicated at 48 to provide upstanding legs 49 and 50, and to provide clearance for the handle when in its lowermost position. The top surfaces of the fixed jaw 16 and of the legs 49 and 50 of the foot plate 11 are parallel with the bottom surfaces 51 and 52 of these respective members and parallel with the tie rod axes. The side surfaces 53 and 55 of the fixed jaw, and the side surfaces 54 and 56 of the foot bracket are also parallel with the axes of the tie rods, while the movable jaw and the combined locking and thrust member are in clearing relation on all sides with planes passing between the fixed jaw and foot bracket, thus permitting the vise to be rested on any one of its four sides for operating on a clamped workpiece from any selected one of four directions. If desired, the legs on the foot bracket may be omitted, or the movable jaw outer surfaces may be made coplanar with the fixed jaw and foot bracket.

This vise is, from the practical standpoint, substantially instantaneous in operation. With the work in place and the lever 47 in a substantially 30 degree angular position as indicated in Fig. 1, the movable jaw with its associated locking and thrust member is merely pushed forward into contact, with the low face of the cam in contact with the jaw, and immediately on contact the lever is depressed to the position shown in dotted lines at 47'. As the lever is moved downwardly, the side cams 37 and 38 first force the plungers 39 and 40 against the flat surfaces on the tie rods which in turn are forced against the opposite walls of their bearings, efficiently locking the member in place. Further downward movement causes the peripheral cam to force the movable jaw forward to grip the work with any desired pressure which is controlled by the degree of movement of the lever, since during operation of the peripheral cam, the plungers are riding on the idling or plane surfaces of the cam at 57. Thus the action with downward movement of the lever is as follows: First, the plungers are forced out to lock the locking member in position, and the plungers ride over the top of the rise on the cam surface just onto the plane surface, and at that point the peripheral cam comes into action on the movable jaw, with any further movement of the lever increasing the grip on the work. For release of the work, the lever is merely raised to the position shown in Fig. 1 and pulled back.

I claim:

1. A quick acting vise comprising, a frame including a fixed jaw and a foot bracket and tie rods rigidly connecting said fixed jaw and foot bracket, a movable jaw slidable on said tie rods, a combined locking and thrust member slidable on said tie rods and coupled to said movable jaw for limited movement, a cam mounted in said combined locking and thrust member and

having side cam faces and a peripheral cam face, with the peripheral cam face cooperative with the back of the movable jaw, plungers slidably operative in bores communicating between said side cam faces and said tie rods for locking said combined locking and thrust member in position, and a lever for operating said cam.

2. A structure as defined in claim 1; said peripheral cam face being located in follow relation to the side cam faces for operation in sequence with operation of the lever for clamping work in the vise.

3. A structure as defined in claim 1; the adjacent sides of the tie rods being flattened for increased surface cooperation with said plungers, and said side cam faces being limited to a rise of 0.010 inch, and with the peripheral cam surface initiating operation on the movable jaw with cooperation of the plungers with the flat parallel faces of the cam after passing over the rise, for sequentially locking the locking and thrust member in position and increasing the grip on the work in the vise.

4. Locking means for releasably locking a member on spaced tie rods, said member having bearings slidable on said tie rods, said member having a passage parallel with said tie rods, a cam rotatably mounted in said passage and having an operating lever, side cam surfaces formed in the side faces of said cam and in opposition, plungers slidable in passages provided in said member and cooperative between said side cam surfaces and said tie rods, for forcing said plungers against said tie rods with the plungers in turn forcing the tie rods with the plungers against the opposite sides of the bearings, to lock the member in its adjusted position on the tie rods.

5. A structure as defined in claim 4; said cam having a peripheral cam surface, a second member slidable on said tie rods and having connection with said member for limited relative reciprocal movement and cooperative with said peripheral cam surface, with said cam through limited degree of rotation sequentially locking said member in position followed by advance of said second member through the medium of said peripheral cam surface.

6. A structure as defined in claim 4; said cam having parallel faces with the side cam surfaces formed in one portion on opposite sides and having a rise of not to exceed 0.010 inch and having a peripheral cam surface with a rise of not to exceed 0.016 inch, a movable vise jaw slidable on said tie rods and having connection with said member for limited relative movement, and with said cam, during depression of said lever, initially forcing said plungers against said tie rods to lock the member in position through the medium of said side cam surfaces, and upon reaching the limit of rise, idling on the parallel faces and coincidentally forcing said movable jaw forward through the medium of the peripheral cam surface cooperating with the back of said jaw.

7. A cam for producing lateral and frontal thrust comprising a substantially circular disc having parallel faces, a cam surface formed in each side face of said disc within a relatively narrow area, a peripheral cam surface formed on said disc, with rises in the peripheral cam surface in follow relation to the rises in the side cam surfaces, a member cooperative with the peripheral cam surface, and laterally operative members cooperative with the side cam surfaces.

8. A quick acting vise comprising, a combined head bracket and fixed jaw, a foot bracket, spaced

tie rods rigidly connecting said head and foot brackets, a movable jaw slideable on said tie rods and having bearings closely fitting said tie rods, a combination locking and thrust member slideable on said tie rods and having bearings closely fitting said tie rods, a passage formed centrally through said locking and thrust member parallel with said tie rods, a cam rotatably mounted in said passage, a cam surface formed in each of opposite sides of said cam, a peripheral cam surface on said cam and cooperative with said movable jaw, connections between said movable jaw and said locking and thrust member for limiting relative movement therebetween, bores provided laterally from said cam and extending between the cam and said tie rods, plungers in said bores and cooperative between said side cam surfaces and said tie rods with the side cam surfaces forcing said plungers against said tie rods and said tie rods against the opposite sides of the bearings in the member for securing said member in position, with said peripheral cam surface in follow relation to said side cam surfaces, whereby with a limited degree of rotation of said cam said side cam surfaces initially force said plungers to lock said member in position followed by movement of said jaw through the medium of said peripheral cam surface.

10

15

20

25

9. A structure as defined in claim 8; said cam surfaces being limited to a rise of approximately 0.010 inch, with the cam having parallel faces with said side cam surfaces formed in a relatively narrow portion thereof and with the peripheral cam surface operating to advance said jaw after the plungers have attained the position of maximum rise and with the plungers thereafter idling on the parallel surfaces.
